UNITED STATES PATENT OFFICE.

WILLIAM J. HALL, OF CINCINNATI, OHIO, ASSIGNOR, BY DIRECT AND MESNE ASSIGNMENTS, TO THE HALL MAILING BOX COMPANY, OF CINCINNATI, OHIO, A CORPORATION OF OHIO.

MAILING-BOX.

1,158,047.

Specification of Letters Patent.

Patented Oct. 26, 1915.

Application filed October 23, 1914. Serial No. 868,328.

To all whom it may concern:

Be it known that I, WILLIAM J. HALL, residing at Cincinnati, Hamilton county, State of Ohio, have invented certain new and useful Improvements in Mailing-Boxes, of which the following is a clear, full, and exact description, attention being called to the drawing which accompanies this application and forms a part thereof.

10 This invention concerns boxes formed out of blanks which contain the sides of the boxes and are cut to a shape so that when such a blank is folded in a certain designated manner, the sides of the box may be arranged to engage each other in proper relative position to form the box and to close the same. The usual material for such blanks is heavy paper, card-board, or paste-board.

20 The principal object of this invention is to produce a box of this character which, after having been formed out of the blank therefor, retains its shape and the sides of which maintain their respective relative positions and also their box-closing engagement with each other without the aid of additional sustaining means such as wrapping paper, twine and devices involving the use of an adhesive substance like so-called 30 "stickers." This feature renders this box a very desirable medium for shipping purposes in any manner as for instance through the mails and more particularly through the parcels post service thereof, inasmuch as 35 the arrangement is such that inspection of the contents is rendered possible without impairing the security of the box.

Another object of the invention is to construct these boxes in a manner that the 40 blanks required therefor may be produced with the least possible waste of material.

The invention consists of certain features and constructions as hereinafter described and claimed and as illustrated in the accompanying drawing in which:

Figure 1. shows at reduced scale a plane view of a blank shaped in a certain manner so that, when folded up as intended, a box as contemplated by my invention may be produced. Fig. 2. is a perspective view and shows the blank and its parts while being bent and folded up for the purpose of forming the box. Fig. 3. is a cross-section between the ends of the completed box. Fig. 5. 50 is a vertical longitudinal section of the

completed box. Fig. 5. in a part of the longitudinal section, illustrates a modified construction of the box.

In the drawing letter A indicates the bottom of the box.

Letters B—B indicate the contiguous sides thereof. The top is formed by two flaps C—C which are overlapped for the purpose, one contiguous to each one of the sides and continuous therewith. These sides are held to each other by locking-flaps D—D at one end of the box and by locking-flaps E—E at the other end and when said flaps are interlocked with each other as shown in Fig. 3. These locking-flaps form continuous parts of sides B—B, extending from their upright edges, there being such a flap at each one of these edges. When so interlocked, they hold these sides in proper relative position with reference to each other and to bottom A. To permit such interlocking, these locking-flaps are notched as shown at d—d and at e—e respectively, and their inter-engagement is effected in the manner illustrated in Fig. 2, and while sides B—B are being bent up to position. Before this is done a flap F at one end of bottom A is bent up so as to be inside of flaps E—E after they are engaged with each other. The object and function of this flap will be presently explained. After the box 75 so formed, has been packed and is ready for closing, flaps C—C are first pressed down and lapped, one over the other, to form the top. A closing flap forming an extension 80 of bottom A is now wrapped entirely around the box and in a manner that part G of it, lies against one end of the closed box, and covers the interlocked flaps D—D, so as to hold them in flat. Another part H, continuous with part G covers the overlapped flaps C—C which form the top and holds them down flat. Another continuous part K lies against the other end of the closed 85 box and covers the interlocked flaps E—E 90 at this end and holds them in flat. This closing flap after having been passed around the box so as to cover the parts mentioned and in the manner stated, is held in place by means of a locking tongue L at its end and of which it forms a continuous part. For such purpose this tongue is pushed in 95 between the engaged flaps E—E and the up-standing flap F as shown in Fig. 4. It is held in position between these parts by fric-

tional resistance due to close contact, also by clamping action upon said tongue, for it is to be remembered in this connection, that at that time the box is packed, and the 5 contents thereof by bearing against flap F, hold it and press it more or less outwardly and against the inter-hooked locking-flaps E—E. Irrespective of any such effect and action of the contents of the box, there is 10 nothing which would favor disengagement of this tongue because such disengagement presumes a bending of the material of the tongue at points which constantly shift as the tongue is drawn out. The material of 15 the tongue however, resists such bending by tending to retain its shape. Nevertheless the engagement whereby this tongue is so held is not permanently fixed and readily yields if positive action is applied when access to the contents is desired.

The blank shown in Fig. 1 is of a shape which, by reason of the narrow but long extension H, K, L does not favor economical blanking of material and also limits the 25 capacity of the press by reducing the number of blanks which may be cut out at a time. To obviate this, this piece may be cut out separately and pasted to the main blank. The additional material, to the extent used 30 would serve to strengthen the main blank and preferably that part thereof which is to form the bottom of the box. Fig. 5 illustrates this part of the construction, letter *a* indicating the material used to make the 35 connection, said material being pasted to bottom A.

As will be seen a box so constructed may be quickly formed from the blank and after closed is securely held so, within the pur- 40 port of the invention, without the use of any auxiliary fastening means.

Having described my invention, I claim as new:

1. A mailing box formed of a one-piece 45 blank which comprises a bottom, side-walls contiguous thereto, end-flaps, one at each of the upright edges of the side-walls, means to secure opposite flaps at each end to each other to hold the side-walls in box-forming 50 position, a top-forming flap contiguous to each side-wall, said flaps being adapted to over-lap each other to form the top, a flap contiguous to one end of the bottom and adapted to occupy a position between the 55 contents of the box and the interlocked flaps at the adjacent end of the box and close against said flaps, a closing flap which extends from the other end of the bottom

and is adapted to lap over the adjacent end of the box, thence over the top of the box 60 and also over the other end, and a locking tongue on this closing flap adapted to occupy a position between the interlocked flaps at the end of the box last mentioned and the upstanding flap which is inside of these 65 interlocked flaps and next to the contents of the box and whereby this locking tongue is closely confined in position.

2. A mailing box formed of a blank comprising a bottom, side-walls integral with 70 the bottom, a pair of interlocking flaps at each end of the box respectively integral with the side-walls, an upstanding flap integral with one end of the bottom and adapted to occupy a position next to and in contact with the contents of the box, and an elongated flap at the other end of the bottom and constituting a closure for the box, said flap being extended upwardly contiguous with the correlated end, across the box top, 80 and downwardly contiguous with the other end, the end of the flap being bent and upwardly inserted between the upstanding flap and the adjacent pair of interlocking flaps in which position it is held between the two 85 and by the pressure of the contents against the upstanding flap.

3. A mailing box formed of a one-piece blank comprising a bottom, side-walls integral with the bottom, a pair of flaps respectively integral with the side-walls, overlapping above the contents of the box when the latter is closed, an upstanding flap integral with one end of the bottom and adapted to be maintained in upright position by the contents of the box, a pair of interlocking flaps respectively integral with the side-walls and exteriorly adjacent to the upstanding flaps, and a flap attached to the blank at the other end of the bottom and 100 constituting a closure for the box, said flap extending upwardly adjacent to the correlated end passing across the top of the box and passing downwardly adjacent to the other end of the box, and finally having its 105 extremity inserted between the upstanding flap and the adjacent interlocking flaps in which position it is held by the close contact between them.

In testimony whereof I hereunto affix my 110 signature this 22nd day of October, 1914, in the presence of two witnesses.

WILLIAM J. HALL.
